(57) **CLAIM**

The ornamental design for a fascia tissue treatment device with a matrix of nine treatment elements, as shown and described.

DESCRIPTION

FIG. 1 is a front, top perspective view showing the first embodiment of a fascia tissue treatment device with a matrix of nine treatment elements;

FIG. 2 is a front elevational view of the device of FIG. 1; FIG. 3 is a rear elevational view of the device of FIG. 1; FIG. 4 is a right-side elevational view of the device of FIG. 1;

FIG. 5 is a left-side elevational view of the device of FIG. 1;

FIG. 6 is a top view of the device of FIG. 1;

FIG. 7 is a bottom view of the device of FIG. 1;

FIG. 8 is a front, top perspective view showing the second embodiment of a fascia tissue treatment device with a matrix of nine treatment elements;

FIG. 9 is a front elevational view of the device of FIG. 8; FIG. 10 is a rear elevational view of the device of FIG. 8; FIG. 11 is a right-side elevational view of the device of FIG. 8;

FIG. 12 is a left-side elevational view of the device of FIG. 8;

FIG. 13 is a top view of the device of FIG. 8; and,

FIG. 14 is a bottom view of the device of FIG. 8.

The broken lines shown as dashed lines are for the purpose of illustrating unclaimed structure, and form no part of the claimed design.
